UNITED STATES PATENT OFFICE.

JOHN L. MILTON AND JOSEPH E. HOLLAND, OF MEMPHIS, TENNESSEE.

BOLTLESS RAILWAY-RAIL JOINT AND TIE-PLATE COMBINED.

1,104,694.

Specification of Letters Patent. Patented July 21, 1914.

Application filed September 23, 1913. Serial No. 791,356.

To all whom it may concern:

Be it known that we, JOHN L. MILTON and JOSEPH E. HOLLAND, citizens of the United States, residing at Memphis, in the county 5 of Shelby and State of Tennessee, have invented new and useful Improvements in Boltless Railway-Rail Joints and Tie-Plates Combined, of which the following is a specification.

10 The present invention relates to improvements in bed plates for railway joints, as well as to a rail chair which is adapted to fit upon the said bed plate, and to support the meeting ends of two railway rails without 15 the employment of bolts and nuts, or analogous devices, passing through the ends of the rails.

With the above recited objects in view, and others which will appear as the nature 20 of the invention is more fully understood the improvement resides in the construction, combination and arrangement of parts set forth in the following description and falling within the scope of the appended claims.

25 In the drawing, there has been illustrated a simple but satisfactory reduction of the improvement to practice, and in which:

Figure 1 is a perspective view illustrating the improvement in connection with two rail 30 ends. Fig. 2 is a transverse section upon the line 2—2 of Fig. 1. Fig. 3 is a perspective view of the bed plate. Fig. 4 is a similar view of the rail chair.

In the drawings the rails are indicated by 35 the characters R—R, the ties by the characters T—T, the bed plate by the character P and the chair by the letter C.

The bed plate is adapted to have its ends received within suitable recesses formed adjacent the ends of at least two ties T, and the said plate comprises a flat body 1 which is formed upon its outer side with an upwardly inclined flange 2 which overlies the body, while the ends of the said body are 45 bent downwardly to contact with the outer faces of the ties T, as indicated by the numeral 3. The ends 3 are provided with openings through which pass securing members, such as headed elements 4, which enter 50 the ties T and pass transversely and horizontally through the said ties. The plate, adjacent its ends is preferably formed with openings for the reception of securing elements 5 which enter the ties in a vertical direction. 55 By such an arrangement, it will be noted that the recessed ties, as well as the secur-

ing elements for the plate or body effectually secured the said bed plate against vertical, lateral, or longitudinal movement. The inner edge of the plate P is centrally provided with an upturned portion or lip 6 which terminates a suitable distance from the ends of the said plate, and which is disposed between the ties T when the plate is arranged upon the said ties. The flat 65 body 1 of the plate is medially formed at suitable intervals with elongated slots or openings A, one of the said openings being arranged adjacent each of the ends of the plate. 70

The chair C includes a base 7 which has its longitudinal edges upturned to provide rail engaging members 8 and 9 respectively. The members 8 and 9 have their inner faces shaped to agree with the opposite sides of 75 the rails, while their outer faces are vertically straight and arranged in a line slightly beyond the vertical plane of the sides of the rail head. The member 8 is preferably formed with a crest 10 which extends upward flush with the outer face of the said member but which does not interfere with the upper edge or shoulder provided by the said member engaging beneath the balls or 80 heads of the rails R—R. The crest 10 has 85 its upper edge, and especially the central portion thereof arranged in a plane flush with the treads of the rails, while the said crest may incline slightly downwardly in opposite directions from the said central 90 portion. The base 7 of the chair C has its underface formed with a plurality of medially disposed, integrally formed lugs 12, the same being of a substantially rectangular formation and which are adapted to be 95 received within the openings A of the bed plate P when the chair is arranged upon the said plate.

By reference to the several figures of the drawing, it will be noted that the members 100 8 and 9 are arranged upon inturned flanges B and C' provided upon the longitudinal edges of the base 7 of the members C, and the flange B is adapted to be received within the channel or passage provided by the 105 flange 2 of the plate P, the chair being held at an angle until the said portion B is snugly received within the channel of the plate P.

The flange member B is, of course inserted at an angle, and serves as a fulcrum for permitting the flange C' to be forced downwardly upon the body 1 and to have its outer 110

edge frictionally contacted by the lip 6. The lip 6 is in the nature of a resilient element which is adapted to exert a pressure toward the flange 2 of the plate P, and the said lip 5 serves, in conjunction with the lugs 12 which enter the openings A of the plate P, to retain the chair against lateral or longitudinal movement, while the overlying member of the flange 2 bearing against the angular member B prevents an upward movement of the said chair C.

It is, of course to be understood that the securing elements 4 and 5 have been inserted within the ties T, so that the plate P is 15 effectually secured upon the ties before the chair is arranged upon the bed plate. When the chair is arranged upon the bed plate, as described, the rails R—R are slid upon the base 7 and between the members 8 and 9, of 20 the chair C from the opposite ends of the said chair, until the ends of the rails abut, or until the said ends are disposed centrally of the chair.

In addition to the securing elements above 25 referred to, it may be found desirable to employ additional securing elements in the nature of spikes S which enter the ties and which have their heads contact with the flanges B and C of the chair, while the spikes 30 S upon the inner portion of the joint also engage with the outer edges of the base plate P.

From the above description taken in connection with the drawing, it will be noted that we have provided a joint for railway 35 rails which is simple in construction, which dispenses with the employment of nuts and bolts, and therefor obviates the danger incident to the disengagement of the nuts from the bolts incident to the vibration of the 40 joint, and it is thought that the advantages of the device will be apparent to those skilled in the art to which such inventions appertain without further detailed description.

Having thus described the invention, what 45 is claimed as new is:

1. In combination with rail ties, a bed plate upon the ties and having its ends flanged and secured to the ties, said plate having its outer longitudinal edge provided 50 with an angular flange which overlies its base and its inner edge centrally formed with a longitudinally extending resilient lip, a chair adapted to be received upon the base and to be engaged by the flange and lip of the 55 said base, and independent means arranged between the chair and plate for sustaining the chair against longitudinal movement upon the plate.

2. In combination with rail ties having 60 depressions adjacent their ends, of a bed plate

arranged within the depressions, the ends of the bed plate being down-turned and secured to the outer faces of the ties, one of the longitudinal edges of the bed plate being formed with an inturned angular flange, the 65 opposite longitudinal edge of the said plate being centrally formed with an upturned elongated resilient lip, the plate having depressions, a rail chair having its inner face formed to receive rails, said chair having its base upon its under face provided with lugs and its longitudinal edges flanged and adapted to be inserted upon the base of the bed plate and to have its opposite edges engaged by the flange and lip of the said bed 70 plate and its lugs received within the depressions in the bed plate.

3. In a device of the class described, in combination with rail ties, a bed plate arranged within depressions provided in the tops of the ties, said plate having its outer edge formed with a flange which overlies its base, the inner longitudinal edge of the plate being formed with an upturned lip disposed between the ties, the ends of the plate being 85 downturned to engage with the outer faces of the ties, and means co-acting with the ends for securing the said ends to the ties, a chair adapted to be received upon the base plate, means for securing the chair upon 90 the base plate, and the flange and lip of the base plate adapted to engage with the opposite longitudinal edges of the said chair.

4. In a device for the purpose set forth, in combination, ties, a base plate having down-turned ends arranged upon the ties and their ends secured to the tie, said base plate also connected with the ties, the outer longitudinal edge of the base plate having an angular inturned flange, a chair, two rails adapted to 100 have their ends arranged within the chair, said chair including a base which is adapted to be secured to the bridge plate and to the ties, said chair having its opposite longitudinal edges flanged and adapted to be received between the flange of the bed plate and the lip thereof, the said chair being provided with sides which have their inner faces shaped to correspond with the fishing spaces of the rails and their outer faces vertically straight, and the straight faces of the outer side member being provided with a rail-engaging crest.

In testimony whereof we affix our signatures in presence of two witnesses.

JOHN L. MILTON.

JOSEPH E. HOLLAND.
